UNITED STATES PATENT OFFICE.

MARCUS DE LAFAYETTE HUSTON, OF KOKOMO, INDIANA.

AUTOMATIC CAR-COUPLING.

1,372,817.

Specification of Letters Patent. Patented Mar. 29, 1921.

Application filed November 16, 1917. Serial No. 202,357.

To all whom it may concern:

Be it known that I, MARCUS DE LAFAYETTE HUSTON, a citizen of the United States, residing at Kokomo, in the county of Howard and State of Indiana, have invented certain new and useful Improvements in Automatic Car-Couplings, of which the following is a specification.

This invention relates to car couplers and has for its object the production of a simple and efficient car coupler which is yieldably held in an open position, and will automatically lock when the jaws of the coupler are swung to a closed position.

Another object of this invention is the production of a simple and efficient coupler which will normally remain in an open position for the purpose of permitting the coupler to receive the coupling head of an adjacent car.

With these and other objects in view, this invention consists of certain novel constructions, combinations and arrangements of parts as will be hereinafter described and claimed.

In the drawings:

Figure 1 is a top plan view of the car coupling,

Fig. 2 is a section taken on line 2—2 of Fig. 1,

Fig. 3 is a section taken on line 3—3 of Fig. 2,

Fig. 4 is a section taken on line 4—4 of Fig. 2,

Fig. 5 is a detail perspective view of a spring which may be used in place of the spring shown in Fig. 1, for holding the swinging jaw in an open position,

Fig. 6 is a top plan view of a modified form of my invention,

Fig. 7 is a side elevation of the structure shown in Fig. 6,

Fig. 8 is a section taken on line 8—8 of Fig. 6,

Fig. 9 is a section taken on line 9—9 of Fig. 8.

By referring to the drawings, it will be seen that 1 designates the draw bar which is provided with an enlarged head 2 for the purpose of supporting a stationary jaw 3 and a swinging jaw 4. The stationary jaw 3 is fixedly secured to the head 2 of the draw bar 1 and the swinging jaw 4 is pivotally connected to the head 2 by means of a pivot pin 5. The stationary jaw 3 is provided with a curved outer end 6 and the swinging

jaw 4 is provided with an inwardly extending lip 7. A stay-bolt 8 is carried by the swinging jaw 4 and works within a slot 9 formed in the head 2. The pin 8 is of less 60 diameter than the width of the slot 9 and therefore allows a slight swinging movement of the swinging jaw 4. The slot 9 may of course be constructed in any desired manner to permit the desired amount of swing 65 of the jaw 4 as for instance by cutting a notch 10 in one side of the slot 9 to permit the path of travel of the stay bolt 8 to be lengthened. This stay bolt 8 extends above the upper face of the jaw 4 and limits the 70 rearward expansion of the spring 11 as is clearly shown in Fig. 2 of the drawings. An expansion spring 12 is anchored at one end to a pin 13 carried by the stationary jaw 3 and the opposite end of the spring 12 75 is secured to a pin 14 carried by the outer end of the swinging jaw 4. This expansion spring 12 is provided with convolutions 15 intermediate the ends thereof and a coupling pin 17 passes down through the jaw 4 and 80 is adapted to drop into the slot 9 of the head 2 and lock the jaw 4 in a closed position, when the jaw 4 is swung inwardly. The coupling pin 17 is carried by a head 18 and this head 18 is provided with a vertically 85 extending slot 19 within which slot 19 works a lug 20 carried by the coupling pin 17 for limiting the longitudinal movement of the coupling pin 17 within the head or cap 18. This coupling pin 17 as shown in Fig. 1, 90 for the purpose of convenience is extended down through the convolution 15 formed in the spring 12.

The jaws of the coupler are shown in a closed position in Figs. 1 and 3 of the drawings and are held in a closed position by means of the coupling pin 17. This coupling pin however passes through the jaw 4 and rests upon the upper face of the draw bar 1, when the jaw 4 is in an open position. As 100 soon as the jaw 4 is swung to a closed position, the coupling pin 17 will, through force of gravity drop into the slot 9 thereby locking the jaw 4 in a closed position. The jaw 4 is provided with alined apertures 16 for 105 the purpose of permitting the coupling pin 17 to extend therethrough.

As shown in Fig. 5 a spring 12 may be replaced by means of a flat spring 22, which flat spring may be secured at its terminals 110 23 to the respective posts 13 and 14.

In Figs. 6, 7 and 8 there is shown a modi-

fied form of the present invention wherein a draw bar 24 is employed carrying a stationary jaw 25 at one end thereof. A swinging jaw 26 is pivotally secured to the head 27 of the draw bar 24 upon a pivot pin 28. The jaw 26 is provided with an overhanging lip 29 for the purpose of engaging an adjacent coupler. An expansion spring 30 is secured at its respective ends to the anchoring pins 31 carried by the respective jaws 25 and 26.

The stationary jaw 25 is provided with shoulder portions 32 and these shoulder portions 32 are adapted to limit the swing of the lugs 33 carried by the swinging jaw 26.

15 A coupling pin 34 is carried by the swinging jaw 26 and this coupling pin passes through apertures 35 formed in the jaw 26 and is adapted to extend through the aperture 36 formed in the draw bar 24, for the purpose of locking the swinging jaw 26 in a closed position when the jaw 26 is swung inwardly. The apertures 35 and 36 are adapted to register for the purpose of permitting the coupling pin 34 to lock the swinging jaw 26 in a closed position. A slotted cap guide 37 is provided for coupling pin 34 and this slotted cap 37 receives a laterally extending lug 38 of the coupling pin 34, for limiting the downward movement of the coupling pin 34 through the apertures 35 and 36.

By considering Fig. 6 it will be seen that lugs 33 will limit the outward swing of the jaw 26 by engaging the shoulder portions 32. The swinging jaw 26 is adapted to be yield-

ably held in an open position by means of 35 an expansion spring 30.

When an adjoining coupler engages or is forced against the inner ends of the swinging jaw 4, the jaw 4 is swung to a closed position and is held in this position by the coupling pin 17.

A spring similar to spring 30 may be used in the form shown in Fig. 1 and anchored to a pin 13^a.

It should be understood that by having the 45 coupling pin mounted in the manner set forth, the pin will be free to drop into aperture 16 formed in the lower extension of the jaw 4 and at the same time the guide will limit the upward and downward movement 50 of the lower end of the pin and will form a long bearing for the pin.

What is claimed is:—

In a car coupler, a T draw bar provided with a longitudinal slot, a bifurcated knuckle 55 pivotally mounted to one side of the T head and straddling said side of the head, an obturator extending from said knuckle into said slot and allowing a limited movement of the knuckle relative to said T and a locking pin carried by the knuckle and adapted to extend through the slot.

In testimony whereof I affix my signature in presence of two witnesses.

MARCUS DE LAFAYETTE HUSTON.
